US0D1025239S

(12) United States Design Patent (10) Patent No.: US D1,025,239 S
(45) Date of Patent:  Apr. 30, 2024

(54) O ALPHABET BEAR STATUE

(71) Applicant: Kunming Chuntian Flower Co., Ltd.,
Kunming (CN)

(72) Inventor: Jinghui Zhong, Fu'an (CN)

(73) Assignee: Kunming Chuntian Flower Co., Ltd.,
Kunming (CN)

() Term: 15 Years

(21) Appl. No.: 29/877,429

(22) Filed: Jun. 6, 2023

(51) LOC (14) Cl. 21-01

(52) U.S. Cl.

USPC D21/604
